FLAPPING WING TOY

William Eugene Polk, New York, N. Y.

Application September 6, 1956, Serial No. 608,262

2 Claims. (Cl. 46—124)

This invention relates to an amusement device or toy, and more particularly to a toy of the flapping wing type.

This invention is an improvement over the flapping wing toy shown in my prior patents, such as Patents Nos. 2,637,935, 2,637,937, 2,637,938, and 2,637,939.

The object of the invention is to provide a flapping wing toy which includes wings and body portions which resemble a fanciful creature such as a butterfly or the like, there being a manually operable means for actuating the toy.

Another object of the invention is to provide a flapping wing toy which is an improvement over the toys of my prior patents in that there is provided a novel means for connecting the wings and body portions to the handles so that by actuating the handles the wings and body portion will be moved to thereby increase the attractiveness of the device.

A still further object of the invention is to provide a flapping wing toy which is adapted to be used by children or the like whereby the children can readily grip the device in the hands and move the handles so that the wings of the device will flap or move back and forth whereby the users will be provided with much amusement and pleasure.

A further object of the invention is to provide a flapping wing toy which can be easily and inexpensively made, the toy of the present invention adapted to be easily assembled or manufactured.

These, together with other objects and advantages which will become subsequently apparent, reside in the details of construction and operation, as more fully hereinafter described and claimed, reference being had to the accompanying drawings forming a part hereof, wherein like numerals refer to like parts throughout, and in which:

Figure 1 is a top plan view illustrating the flapping wing toy of the present invention.

Figure 2 is a sectional view taken on the line 2—2 of Figure 1.

Figure 3 is a fragmentary bottom plan view of the toy of the present invention.

Figure 4 is a front elevational view of the toy.

Figure 5 is a view showing the handles detached.

Figure 6 is a view showing one of the sections detached from the handle.

Figure 7 is a bottom plan view illustrating the wings in raised position.

Figure 8 is a front elevational view showing the wings in raised position.

Figure 9 is a fragmentary side elevational view with parts broken away and in section showing a modified arrangement.

Figure 10 is a fragmentary sectional view illustrating a further modified arrangement.

Figure 11 is a fragmentary front elevational view with parts broken away and in section, and illustrating a further modification.

2

Figure 12 is a fragmentary sectional view illustrating a still further modification.

Referring in detail to the drawings, the numeral 10 indicates a flapping wing toy which includes a pair of handles 11, and the handles 11 are provided with flanges 12 intermediate the ends thereof. A pivot pin 13 extends through the flanges 12 so as to pivotally connect the pair of handles 11 together.

Each of the handles 11 has the same construction, and each includes a curved hand gripping portion 14 and a shank or stem portion 17, Figure 5. There is further provided a coil spring 15 which is interposed between the pair of hand gripping portions 14, and the ends of the coil spring 15 may be seated in the countersunk recesses 16 in the hand gripping portions 14.

Each of the shanks 17 of the handles 11 is provided with a slot 18 for a purpose to be later described. The toy 10 further includes a pair of sections 19, and the sections 19 have the same shape and construction. The

sections 19 may be attractively decorated so as to resemble the wings of a fanciful creature such as a butterfly or the like, or a bird, and the sections 19 may be provided with bells so that as the handles 11 are actuated, not only will the device provide a pleasing appearance, but also such bells will help to increase the pleasure derived from the toy, since the bells will ring when the sections 19 are flapped or moved by the handles. Each section 19 includes a wing portion 20 and a body portion 21. The body portions 21 are formed integral with the wing portions 20, but the body portions 21 are arranged at approximately a 90 degree angle with respect to the wing portions 20, as for example as shown in Figure 8. Each body portion 21 has a resilient band 22 arranged in encircling relation therewith, Figure 4. Thus, the resilient or rubber band 22 encircles or surrounds the body portions 21. The body portions 21 are provided with notches or cutouts 24 for receiving the band 22.

The lower sections of the body portions 21 are each provided with a pair of opposed cutouts or notches 25, and resilient or rubber bands 23 are arranged in engagement with the notches 25. The resilient bands 23 are also arranged in engagement with the slots 18 in the shanks 17 so that as the handles 11 are moved towards and away from each other or pivoted about the pin 13, the body portions 21 and wings 20 will be flapped or moved so that a highly pleasing effect will be achieved.

Referring to Figure 9 of the drawings there is shown a modified flapping wing toy which is indicated generally by the numeral 26, and the toy 26 includes a pair of handles 27 which are pivotally connected together in the same manner as the previously described handles 11.

However, in Figure 9 there is shown a different means for attaching the body portions 21 to the handles 27. Thus, extending forwardly from an end of each of the handles 27 is a pin or rod 28 which may have an enlarged head 29 on an end thereof. Resilient or rubber bands 30 are arranged in engagement with the rod 28, and the bands 30 are connected to the body portions 21. Thus, by placing the hand in engagement with the portions 31 of the handles 27, the handles 27 can be pivoted about the pin 32 so that the wings 20 and body portions 21 can be caused to move so as to impart to the toy a highly realistic or life-like appearance.

Referring to Figure 10 of the drawings, there is shown a further modified flapping wing toy which is indicated generally by the numeral 32. The toy 32 includes a pair of handles 33 which are pivotally connected together by means of a pivot pin 35, each handle 33 including a hand gripping portion 34. Each of the handles 33 is further provided with an offset portion 36 which has a rod or pin 37 extending therefrom. The rod 37 is arranged in engagement with bearings 40 which are

secured to or formed integral with the body portions 38, and the body portions 38 being arranged at an angle with respect to the pair of wing portions 39. Thus, by manually engaging the portions 34 of the handles 33 and pivoting the handles about the pin 35, the rods 37 will move so that the wings 39 will flap to thereby provide the desired effect.

Referring to Figure 11 of the drawings there is shown a still further modified toy which is indicated generally by the numeral 41. The toy 41 includes a pair of pivotally mounted handles 42 which each have hand gripping portions 43. Each handle 43 is provided with a slot or cutout 44, for a purpose to be later described. The toy shown in Figure 11 further includes a pair of similar sections 45 which may be colored or otherwise arranged to represent the wings of a fanciful creature such as a butterfly, bird or the like. Each section 45 includes a wing 46 and a body portion 47. Extending from each body portion 47 is a curved flange 48, and the flanges 48 extend through the slots 44 in the handles 42. A rubber band 49 is arranged in surrounding relation with respect to the pair of body portions 47. Thus, when using the toy 41 shown in Figure 11, the hand gripping portions 43 are actuated to thereby move the handles and this causes the pair of body portions 47 to move towards and away from each other since the flanges 48 are arranged in engagement with the slots 44. As the body portions 47 move, the wings 46 will have a flapping motion as indicated by the solid and dotted line positions in Figure 11.

Referring to Figure 12 of the drawings there is shown a still further modification which is indicated generally by the numeral 50. The toy 50 shown in Figure 12 includes a pair of similar sections 51, and each section 51 includes a wing portion 52 and a body portion 53. There is further provided a pair of pivotally mounted handles 54 which are connected to the body portions 53 by means of rubber bands 55. There is further provided a body member 56 which is positioned between the pair of body portions 53, and the member or element 56 is connected to the body portions 53 by means of a pair of rubber bands 57 and 58.

From the foregoing, it is apparent that there has been provided a flapping wing toy which is an improvement over the toys shown and described in my prior patents. In use, the curved portions 14 of the handles 11 are gripped in the person's hands and then the portions 14 are moved towards each other so as to compress the spring 15. This causes the handles 11 to pivot on the pin 13 so that the shanks 17 will move away from each other and this will cause the pair of body portions 21 to move since the body portions 21 are connected to the shanks 17 of the handles 11 by means of the rubber bands 23. The rubber bands 23 extend through the slots 18 in the shanks 17 of the handles. Thus, as the handles 11 pivot, the body portions 21 will move towards and away from each other whereby the wings 20 will flap so that the toy will simulate a flying butterfly, bird or the like. As previously described, the wing portions 20 and the body portions of the device are preferably colored or designed so that they have the appearance of a life-like bird, butterfly or other creature. When pressure on the portions 14 is released, the coil spring 15 will move the portions 14 away from each other so that the handles 11 will be moved whereby the body portions 21 and wings 20 will again be moved. Thus, by continuously applying pressure to the portions 14 and releasing pressure on the portions 14 a continuous flapping motion can be imparted to the wings 20 whereby the device will have the appearance of a bird or the like in flight.

As previously described, the rubber band 22 is arranged in engagement with the notches 24, and the rubber band 22 is positioned at the junction of the body portions 21

and the wings 20, the rubber band 22 serving to connect the pair of sections 19 together.

Referring to Figure 9 of the drawings, there is shown a modified arrangement wherein the handles 27 are provided with the pins 28 which have the rubber bands 30 arranged in engagement therewith, the rubber bands 30 being connected to the notches 25 on the body portions 21. Thus, by moving the handles 27, the body portions 21 and wings 20 can be caused to move. Thus, it will be seen that in Figure 9 the slots 18 are not used.

Referring to Figure 10 of the drawings there is shown a still further modified arrangement which is constructed so that by gripping the portions 34 and pivoting the handles 33 about the pin 35, the pair of rods 37 will move towards and away from each other. As the rods 37 move, they cause movement of the body portions 38 and the body portions are connected to the rods 37 by means of the bearings 40. The body portions 38 are formed integral with or secured to the wings 39 so that as the handles 33 are moved, the wings 39 will have a flapping motion.

In Figure 11 there is shown a still further modified arrangement and in Figure 11 movement of the handles 42 causes the wings 46 to flap or move since the flanges 48 are arranged in engagement with the slots 44 in the handles 42.

In Figure 10 there is provided a rubber band 59 which serves the same purpose as the previously described rubber band 22.

Referring to Figure 12 of the drawings there is shown a still further modification wherein the element 56 is positioned between the pair of body portions 53 of the sections 51, and the element 56 may be held in place by means of rubber bands 57 and 58. Thus, by manually pivoting the handles 54, the body portions 53 will move and this will cause the sections 51 to move so that the wings 52 can be given a flapping motion.

The construction of the flapping wing toy of the present invention permits the wing sections to be quickly attached to the handles as during fabrication or assembly of the toys. With the present invention the wing sections are easily connected together and also the sections are readily connected to the handles. Thus, as shown in Figures 1 through 8, the sections 19 are connected together by means of the rubber band 22, and the sections 19 are connected to the handles 11 by means of the rubber band 23. The coil spring 50 assists in returning the handles to their normal positions after the closing hand pressure is released from the hand grip portions 14. As the handles are opened and closed, the wings will spread apart and close and the flexible bands will permit sufficient rotary motion of the wings but the bands will also hold the wings in their proper relation to each other and to the handles. The provision of the pivot pin 13 and the flanges or shoulders 12 provides a stable arrangement which will not bind. In Figure 10 the bearings 40 rotatably receive the rods 37. The bearings 40 may consist of straps or the like. In Figure 11 the curved portions or flanges 48 are formed integral with the body portions 47 or secured thereto, and in the arrangement shown in Figure 11 no springs are necessary for connecting the body portions to the handles. However, in Figure 11 the sections 45 are connected together by means of the spring member 49. The flexible band 22 tends to keep the wings in down or spread position so that the spring 22 assists the handle spring 15 in closing the handles. In certain instances the band 22 may be used with or without other flexible bands and with or without the spring 15. In Figure 12 there is shown a separate body section 56 which is not physically connected to the wing sections except by means of the flexible bands 57 and 58. Thus, the body section 56 is held between the portions 53 and the arrangement shown in Figure 12 provides a simple and effective method of attaching the body section 56 and

the wing sections 51 together so as to permit free up and down movement of the wings when the handles 54 are operated.

I claim:

1. In a flapping wing toy, a pair of handles, a pin pivotally connecting said handles together intermediate the ends thereof, each of said handles being shaped to include a curved hand gripping portion on one end thereof, a coil spring interposed between said hand gripping portions, each of said handles further including a shank on the other end thereof, there being a slot in each of said shanks, said shanks being mounted for movement towards and away from each other, said hand gripping portions being mounted for movement towards and away from each other, a pair of similar sections each shaped to include a wing and a body portion, said body portions being arranged angularly with respect to said wings, there being notches in said body portions, a resilient band encircling said body portions and engaging said notches, each of said body portions being provided with a pair of opposed notched areas, and resilient bands extending through said slots and engaging said notched areas on the body portions.

2. A flapping wing toy comprising a pair of handles, said handles being provided with flanges intermediate the ends thereof, a pin pivotally connecting said flanges together, each of said handles having the same construction and said handles being shaped to embody a curved hand gripping portion on one end thereof, a coil spring

interposed between said hand gripping portions, the ends of the coil spring being seated in countersunk recesses in the hand gripping portions, each of said handles further embodying a shank on the other end thereof, there being a slot in each of said shanks, said shanks being mounted for movement towards and away from each other, said hand gripping portions being mounted for movement toward and away from each other, a pair of similar sections each shaped to embody a wing and a body portion, said body portion being arranged at approximately a 90° angle with respect to said wings, there being notches in said body portions, a resilient band encircling said body portions and engaging said notches, each of said body portions being provided with a pair of opposed notched areas, and resilient bands extending through said slots and engaging said notched areas on the body portions so that as the handles are moved towards and away from each other or pivoted about the pin, the body portions and wings will be flapped or moved so that a highly pleasing effect will be achieved.
